UNITED STATES PATENT OFFICE.

GEORGE M. EATON, OF PITTSBURGH, PENNSYLVANIA, ASSIGNOR TO WESTINGHOUSE ELECTRIC & MANUFACTURING COMPANY, A CORPORATION OF PENNSYLVANIA.

FLEXIBLE LOCOMOTIVE DRIVE.

Application filed May 11, 1921. Serial No. 468,595.

To all whom it may concern:

Be it known that I, GEORGE M. EATON, a citizen of the United States, and a resident of Pittsburgh, in the county of Allegheny 5 and State of Pennsylvania, have invented a new and useful Improvement in Flexible Locomotive Drives, of which the following is a specification.

My invention relates to flexible driving 10 connections and more particularly to means for equalizing the pulling strains between a plurality of driving gears that are operatively associated with a common driven element.

15 The object of my invention is to so mount a plurality of driving pinions that, when they are in mesh with a single gear or with a plurality of rigidly connected gears, variations in the quality of engagement between 20 the teeth of any one pinion and its associated gear with respect to the engagement between the teeth of another pinion and its gear will be compensated for and not result in excessive driving strains upon either of 25 the pinions.

Furthermore, my construction provides 30 flexibility between the rotor elements with which the respective pinions are connected, in those cases where such pinions serve as driving connections for a plurality of motors driving a single shaft.

It has been proposed, in electric locomotive construction, to mount the motors in pairs, with pinions on their respective shafts 35 meshing with the gear wheels carried on a jack shaft, the motors being placed at opposite sides of the jack shaft.

This arrangement is objectionable, because inequality of engagement by the pinions of one shaft with the gear wheels results in excessive strains on the other pinions, at least temporarily. Likewise, variations in the engagement between the pinions of one motor and the gears and in the engagement between the gears and the pinions of the other motor may cause the temporary imposition of an excessive load on one of the motors.

One means for applying my invention is 40 shown in the accompanying drawing, wherein—

Figure 1 is a view, in side elevation, showing a portion of a locomotive constructed in accordance with my invention.

45 Fig. 2 is a plan view of the structure

shown in Fig. 1, except that the cab body is omitted.

Fig. 3 is a detail view of one of the flexible elements, and

Fig. 4 is a view taken on the line IV—IV 50 of Fig. 3.

A locomotive body 4 is mounted upon a supporting structure 5 embodying the usual side frames 6 that are carried by axles 7 and 8, and in which is journaled a jack shaft 65 9. The side frames also support a pair of motors 10 and 11 that are provided with armature shafts 12 and 13, respectively.

The jack shaft 9 carries, at its opposite ends, gear wheels 15 and 16 that are connected to driving wheels 17 and 18, respectively, through side rods 19 and 20.

The gear wheels 15 and 16 are preferably of the flexible type such, for instance, as that described in my Patent No. 1,321,512 issued 75 Nov. 11, 1919, in order to provide flexibility between the driving wheels 17 and 18 and the rims of the gear wheels.

The armature shaft 13 is provided with 80 pinions 21 and 22 and the armature shaft 12 is provided with pinions 23 and 24.

Owing to the difficulty of making comparatively small pinions of the flexible type described in the patent above referred to, I prefer to make them of the type of those 85 shown in my Patent No. 1,306,531, issued June 10, 1919.

It is not feasible to provide flexibility in the pinions 21 and 22, because of their comparatively small size and because a flexible 90 connection, such as is shown between the pinions 23 and 24 and the armature shaft 12, would interfere with the movement of the side rods 19 and 20.

Although the gear wheels 15 and 16 may be provided with resilient connections between their centers and their rims, as above pointed out, the motors 10 and 11 would be rigidly connected through the rims of the gear wheels, if flexibility were not provided in one of the pinions. An important feature of my invention resides in the means whereby flexibility is secured between the motors in a drive of this general type.

The pinions 23 and 24 are rigidly secured 100 to the sleeve members 27 and 28 that surround the ends of the shaft 12. The sleeve members are connected to the shaft 12, through projections 29 and 30, springs 31 and arms 110 34 and 35 of a quill member 36 that is rig-

idly held in place upon the shaft 12, by a nut 37, as shown more clearly in Fig. 4.

It will be seen from the foregoing that each motor is protected against shocks or excessive stresses as a result of inequality in gear teeth or other abnormal conditions.

It is apparent that various changes in the general arrangement may be made, such, for instance, as by the employment of a flexible 10 element of a different type for the various pinions, or for some of them. Various other modifications may be made without departing from the spirit of the invention, as defined in the accompanying claims.

15 I claim as my invention:

1. In combination, in a locomotive, traction wheels, a jack shaft extending transversely of the locomotive, gear centers mounted on the jack shaft, side rods connecting the traction wheels to the gear centers, gear rims carried by the gear centers, flexible elements enclosed between the gear rims and the gear centers, a pair of motors disposed on opposite sides of the jack shaft, 25 and armature shafts driven by the motors and each provided, at its opposite ends, with pinions that mesh with the respective gear rims, the pinions of one of the said armature shafts being flexibly mounted.

2. The combination with a driven member, of a plurality of drive members, said driven and one of said drive members being rotatably yieldable.

3. The combination with a pair of motors, 35 of a driven member geared thereto, said driven member having a flexible connection with the motor gears and one of the motor shafts having a flexible element on the respective ends thereof.

4. The combination, in a driving connection, of two flexible gear wheels, a single shaft therefor, and a motor shaft provided with pinions that mesh with said gear wheels one of the pinions being flexibly mounted.

5. In a driving connection, the combination of a pair of oppositely rotating pinions and an interposed flexible gear wheel, one of said pinions being resilient.

6. In a driving connection, the combination of a pair of driving gear wheels, a shaft therefor, a second pair of driving gear wheels, and a shaft therefor, and two flexible driven gear wheels, each of which has driving connection with one of the driving gear wheels of each of said pairs, one pair of driving gear wheels being resilient.

7. In a driving connection, the combination of a pair of driving gear wheels, a shaft therefor, a second pair of driving gear wheels and a shaft therefor, and two driven gear wheels, each of which has driving connection with one of the driving gear wheels of each of said pairs, one pair of driving gear wheels and the driven gear wheels being resilient.

8. In combination, a driven shaft, a flexible gear wheel on each end of the shaft, a motor provided with an armature shaft that has a flexible pinion on each end meshing with the said gear wheels, and a motor provided with an armature shaft that has a rigid pinion on each end meshing with the said gear wheels.

In testimony whereof, I have hereunto 75 subscribed my name this 21st day of April 1921.

GEORGE M. EATON.
